FIG. 4.

UNITED STATES PATENT OFFICE

2,228,474

APPARATUS FOR DISTILLING OIL SHALE

Edward P. Morrish, St. Louis, Mo.

Application January 19, 1938, Serial No. 185,639

4 Claims. (Cl. 202—129)

My invention relates to the recovery of oil and other products from shale or other material and more particularly to an improved apparatus for accomplishing this recovery.

To obtain the oil from oil shale it is necessary to heat the shale in a retort. The oil is the result of destructive distillation and is driven off in a form of vapor to be later condensed by cooling. Many types of retorts or stills have been constructed to distill shale oil and the most successful have been what is known as the vertical type. No horizontal type of still, although more simple and cheaper to construct, has been made which is successful as they easily become clogged, are hard to clean due to poor design and the shale gases are overheated, thereby decreasing the quality and quantity of oil and making for a generally ineffective and inefficient distillation process. Closed types of stills have been employed to distill shale oil but because of the high pressures or vacuums employed they have not been satisfactory because of the possibility of explosion and also because of their cost.

One of the objects of my invention is to produce an improved distilling apparatus of the open type having its retort positioned substantially horizontal and being operated without substantially greater pressure than atmospheric.

Another object of my invention is to construct a still for the distillation of oil shale which will efficiently and economically remove the vapors from the shale when heated and permit them to be quickly condensed into the desired products.

Another object of my invention is to produce a distilling apparatus for shale oil which will not become easily clogged by any asphaltum base oils and which can be easily and quickly cleaned.

Still another object of my invention is to recover oil from shale by an improved and more efficient method.

Other objects of my invention will become apparent from the following description taken in connection with the accompanying drawings showing apparatus embodying my invention and capable of carrying out my improved distillation process.

Figure 1 is a side view partly in section of my improved still for distilling oil from shale; Figure 2 is an end view of the still taken on the line 2—2 of Figure 1; Figure 3 is a top view of the charging end; Figure 4 is a longitudinal cross-sectional view of a portion of a modified construction; and Figure 5 is a cross-sectional view taken on the line 5—5 of Figure 4.

Referring to Figures 1, 2 and 3, the numeral 1

indicates the main body of the still which in the particular construction shown is cylindrical in shape. One end of this cylinder has welded thereto an annular flange 2 to which is attached by bolts 3 a removable closure plate 4, there being a copper and asbestos gasket 5 to insure perfect sealing. The opposite end of the cylinder also has welded thereto an annular flange 6 and cooperating therewith to close the end of the cylinder is a door 7. The door is held in closed position by a special stamp construction comprising a bracket 8 pivotally mounted on the flange 6 by a pivot pin 9 and having a hooked end 10 for engaging the inner edge of the flange. The central part of the bracket has threaded therein a clamping screw 11 carrying a head 12 for engaging the central portion of the door and a wheel 13 for rotating the screw. The bracket also has a handle 14 for swinging the bracket on its pivot when the door is to be opened. The door is also provided with a slot 15 for receiving a part of the bracket. To open the door it is only necessary to unscrew the screw 11 and then swing the bracket aside.

The cylinder is mounted on four legs 16, the two at the closed or left end of the cylinder being longer than those at the door end in order that the cylinder be slightly inclined to the horizontal. The angle of inclination may vary but should be such as to allow for the heavier oils resulting from the distillation to flow toward the door end where they are drained off through a pipe 17 controlled by a valve 18. If desired, the cylinder could be positioned horizontal and an inclined trough placed in the bottom thereof to permit the heavier oils to flow toward the front end. The legs 16 are braced by suitable braces 19 as shown.

The cylinder has communicating therewith a series of vapor outlet conduits 20, there being four on each side in the particular construction shown. The conduits on one side are joined to a header pipe 21 and those on the other side to a header pipe 22. A special joint 23 is provided between each conduit 20 and its header pipe which will permit the header to be quickly removed so that the conduits and the header pipes may be accessible for cleaning. The point at which the vapor conduits communicate with the interior of the cylinder is very important this point being just above the center of the cylinder. If these outlets were at a lower point the vapors driven off the shale would be overheated and if at a higher point they would not be properly removed. The header pipes rest on brackets 24 on the legs and are connected together at the front end of the still and to a pipe 25 leading to a condensing coil 26 in a water

55

cooled condenser 27. The vapors which are condensed by the condenser to form the crude oil and other products are drawn off through the pipe 28.

5 The bottom side of the cylinder has secured thereto a burner chamber 29 which rests on cross braces 30 between the legs, and positioned in this chamber are the burners 31 which are supplied with gas, oil or other suitable fuel. The chamber 10 29 is covered with asbestos or other heat insulating material as is also the lower part of the cylinder between the conduits 20 and the burner chamber. The upper part of the cylinder is left un-covered.

15 Extending into the cylinder through the rear end plate 4 is a pipe 32 which is connected by a pipe 33 to a liquid tank 34 and controlled by a hand valve 35. The liquid in the tank in most instances will be water but other liquids or rapidly 20 expanding gases may be employed as will be explained subsequently. To permit the temperature in the cylinder and that of the vapors to be readily ascertained, a suitable temperature recorder may be employed, as for example, the thermometer 36 extending into a small dome on the top of the cylinder. In order that the shale 37 may be easily inserted in the cylinder and the residue removed, a cylindrical screen container 38 is employed.

30 The operation of the still and the method of extracting the oil from the shale is as follows: The shale is first crushed to such a size that the vapors can be removed without danger of burning them by any high temperatures in the inner 35 part of the shale. It has been found that if the crushed shale will pass through a one-half inch mesh screen or less, the gases may be properly removed. The crushed shale is then placed in the screen container when it is removed from 40 the cylinder and after putting the charge in the cylinder, the door 7 is clamped in closed position. The burners are now lighted and the cylinder heated. When the temperature in the cylinder has reached about 60 degrees centigrade, oil 45 vapors will begin to be driven off the shale. This temperature should be reached about one-half hour after starting the burners or a sufficient length of time to heat the interior of the shale, which is the coolest, to a temperature substantially the same as that at which the vapor begins 50 to come off. The temperature at which the vapor begins to come off will vary depending upon the type of shale being used, the temperature given being that for Devonian shale which carries a good commercial quantity of oil and other 55 valuable products. When the oil vapors begin to come off, the heat may be increased somewhat but not sufficiently to cause decomposition of the oil vapors.

60 The vapors which have been driven off will also contain relatively non-condensable gases and will rise to the top of the cylinder. The vapors containing oil and other products driven off will have a greater density than these non-condensable gases and will, therefore, begin to separate out and take a position below the non-condensable gases which gases will tend to maintain their positions adjacent the top wall of the cylinder. This separation is assisted by the fact 65 that the top portion of the cylinder is in contact with the atmosphere and, therefore, cooler, thus permitting the oil vapors to condense more rapidly and, therefore, facilitate their separation from the non-condensable gases. The curved 70 top wall of the cylinder also causes the oil laden

vapors to flow toward the outlets as they condense. The vapor containing the oil or other desirable products will thus be approximately above the center of the cylinder and below them will be the vapors containing base oils which 5 are not desired. Since the vapor outlets are just above the center, it is seen that the vapors containing the oils desired will be free to pass out into conduits 20 and into the headers. It is noted that the conduits 20 drop rapidly and being shielded from the heat by the asbestos chamber 29 are, therefore, cooler than the interior of the cylinder. As soon as the vapors move into these cooler conduits, they begin to condense 10 still more rapidly and because of their greater 15 density will drop down the pipe into the headers. The vapors pass from the headers and are condensed in the condenser coil and appear as crude oil.

20 In order to insure that the vapors be driven out of the cylinder from time to time and not allowed to become overheated and decomposed, steam is caused to be formed in the cylinder. This is accomplished by opening the valve 35 and allowing a small quantity of water to pass into 25 the cylinder which will immediately be changed to steam by the high temperature of the cylinder.

The temperature of the cylinder should be progressively increased until it is approximately 30 750 degrees centigrade or such temperature required to completely distill the particular shale being treated. Complete distillation can usually be consummated in about one and one-half or two hours after the vapors begin to come off. The more rapid the distillation caused by a rapid 35 rise in temperature, the larger will be the volume of crude oil secured from the shale whereas on the other hand if the temperature is raised slowly the quality of oil will be better as there is less 40 possibility of overheating the vapors or causing cracking or decomposition on re-distillation. The heavy oils such as those having an asphaltum base flow to the front end of the cylinder and are drawn off from time to time through the pipe 17.

45 When the distillation is complete, sufficient water is admitted to the cylinder to produce sufficient steam to force all the vapors out and then after turning off the burners, the retort is allowed to cool which cooling, if desired, may be accelerated by the continued release in the retort of steam or some non-explosive gas. When the retort has cooled down to about 150 degrees centigrade, the steam or other gas, if not already being employed, is released in the retort 50 in sufficient quantities to maintain a slight positive pressure. The door is then quickly opened and the spent shale quickly removed. By having the steam or gas in the retort at the time the door is opened, air will not be allowed to 55 enter the retort and cause an explosion with its attendant undesirable results. The greatest percentage of oil vapors will be removed without decomposition by having the vapor conduits 20 communicating with the cylinder at the point 60 shown. If the outlets were higher up, only part of the desirable vapors would pass out and the others would be decomposed and if they were 65 lower, some the less desirable products would flow into the vapor outlets.

70 The oil vapors coming off the shale contain different products at different temperatures depending upon the shale used. Among these may be mentioned ethers, naptha, gasoline, kerosene, lubricating oil, and so forth. It is thus seen 75

that if certain products are desired from the shale, they may be taken off at the different temperatures at which the vapors containing them appear in the cylinder.

5 In the place of the introduction of water during the distillation process to cause steam to be formed to force out the vapors, other liquids and gases may be employed. For example, if it is desired to dehydrate the oil vapors, a mixture 5
10 of water and sulphuric acid can be employed or sulphuric acid alone. Rapidly expanding gases which have no reaction with the vapor and are non-explosive can also be used effectively in place of the steam and among these may be mentioned 15
15 the inert gases, nitrogen or carbon dioxide.

Although the still is described as being used for the distillation of shale, it may be employed to distill other substances which require destructive distillation to secure the desired products and, 20 therefore, it is to be understood that the invention is not limited to the distillation of shale only.

Referring to modifications shown in Figures 4 and 5, the cylinder forming the retort and the vapor conduits are of somewhat different construction but the remainder of the still is substantially the same as already described and, therefore, similar parts are indicated by the same numerals. The cylinder 1' is provided with a plurality of longitudinally spaced openings 40 in 25 its top wall 41 which communicate with a chamber 42 positioned above the cylinder and having a curved top wall 43 which is preferably concentric with the top wall of the cylinder. This chamber extends over about 90 degrees and its side wall 44 30 has connected thereto the series of vapor outlet conduits 45 and its side wall 46 has connected thereto the series of vapor outlet conduits 47. The interior of the chamber 42 is provided with baffle plates 48 extending downwardly from the top wall 43 and spaced between the vapor outlets. The compartments between the baffle plates are connected together by openings 49. The upper or left-hand end of the chamber also has communicating therewith a chamber 50 for collecting the relatively non-condensable gases. A valve 51 at the top of the chamber permits these gases to be drawn off when desired. If the gases are combustible, they may be employed in heating the retort after the distilling operation has begun. The top outer surface of wall 43 of chamber 42 is also shown as provided with cooling fins 52. In place of these fins the top wall may be corrugated for increasing the radiating surfaces. The conduits 45 and 47 are connected to the header pipes at the side of the still in a manner already described. The shale 37 is placed in the cylinder 1 in the same manner as shown in Figures 1, 2 and 3.

60 In the modification the desirable oil laden vapors driven off the shale pass through the openings 40 into the chamber 42 where it is cooler than in the cylinder. The vapors carrying the oil and other desired product then separate from 65 the relatively non-condensable gases and assume their level below the gases and opposite the vapor outlets into which they are free to pass. The baffle plates prevent the rapid longitudinal shifting of the gases and tend to confine the gases near the top wall. The curved top wall of the chamber 43 also assists in causing the vapors to move toward the vapor outlets. The separate chamber 42 prevents any of the vapors from going back into the cylinder once they have entered 70 the chamber, thus there is little possibility of the

vapors becoming decomposed on re-distillation or cracking taking place. By having a separate and cooler chamber above the cylinder to permit contraction of the vapors, they will pass out of the retort more rapidly and there is a better separation from the undesirable heavier oil vapors. 5

Having thus described my invention and being aware of the possibilities of modifications, I desire it to be understood that I do not intend that the scope of the invention be limited except 10 as required by the appended claims.

Having fully described my invention, what I claim as new and desire to secure by Letters Patent of the United States is:

1. In an apparatus for destructive distillation 15 of carbonaceous deposits such as oil shale or other carbonaceous material, a stationary elongated hollow member having its longitudinal axis positioned substantially horizontal and adapted 20 to receive a charge of distillable shale or other material containing oil and other products capable of being driven off as a vapor by the application of heat, a chamber above the hollow member and having a top wall the inner surface of 25 which is concave, said chamber being in communication with the hollow member by openings in the top wall thereof, longitudinally spaced vapor outlets at both sides of the chamber, downwardly extending conduits connected to the outlets and 30 having no portion above the outlets, a condenser connected to the conduits, and means for applying heat uniformly to the bottom of the hollow member.

2. In an apparatus for destructive distillation 35 of carbonaceous deposits such as oil shale, a stationary elongated hollow member having its longitudinal axis positioned substantially horizontal and adapted to receive a charge of distillable material containing oil and other products capable 40 of being driven off as vapors by the application of heat, a chamber above the hollow member and having a top wall the inner surface of which is concave, said chamber being in communication with the hollow member by openings in the top 45 wall thereof, longitudinally spaced vapor outlets at both sides of the chamber, downwardly extending conduits connected to the outlets and having no portion above the outlets, baffles extending downwardly from the top wall of the 50 chamber and positioned between the vapor outlets, a condenser connected to the conduits, and means for applying heat uniformly to the bottom of the hollow member.

3. In apparatus for destructive distillation of 55 carbonaceous deposits such as oil shale, a stationary elongated hollow member having its longitudinal axis positioned substantially horizontal and adapted to receive a charge of distillable material containing oil and other products capable 60 of being driven off as a vapor by the application of heat, a chamber above the hollow member and having a top wall, the inner surface of which is concave, said chamber being in communication with the hollow member by openings in the top 65 wall thereof, longitudinally spaced vapor outlets on each side of the chamber and communicating with the chamber at a predetermined distance below the top wall thereof, downwardly extending conduits connected to the outlets, a header pipe connected with the conduits on each side, a condenser connected to the conduits, means for applying heat uniformly to the hollow member, and a non-condensable gas collecting chamber 70 75

positioned above the first named chamber and communicating therewith.

4. In an apparatus for destructive distillation of carbonaceous deposits such as oil shale, a stationary elongated hollow member having its longitudinal axis positioned substantially horizontal and adapted to receive a charge of distillable material containing oil and other products capable of being driven off as a vapor by the application of heat, a chamber above the hollow member and having a top wall the inner surface of which is concave, said chamber being in communication

with the hollow member by openings in the top wall thereof, longitudinally spaced vapor outlets on each side of the chamber and communicating with the chamber at a predetermined distance below the top wall thereof, downwardly extending conduits connected to the outlets, a header pipe connected with the conduits on each side, a condenser connected to the conduits, means for applying heat uniformly to the hollow member, and heat radiating means associated with the exterior of the top wall of the chamber.

EDWARD P. MORRISH.
